UNITED STATES PATENT OFFICE.

JAMES R. BINNS, OF CANTON, OHIO.

EXPLOSIVE-ENGINE STARTER.

1,194,469.

Specification of Letters Patent. Patented Aug. 15, 1916.

Application filed July 26, 1915. Serial No. 41,831.

To all whom it may concern:

Be it known that I, JAMES R. BINNS, a citizen of the United States, residing at Canton, in the county of Stark and State of Ohio, have invented a new and useful Explosive-Engine Starter, of which the following is a specification.

My invention relates to explosive engine starters and has more especial reference to 10 a device, adapted to replace the ordinary crank used for starting automobile engines. This device is adapted for more conveniently turning over the engine shaft, the mechanism being so arranged that the operator may 15 have greater advantage in properly applying the necessary power for starting the engine.

The objects of my invention are, to generally improve engine starters and to provide such a device as may enable the operator 20 to start the engine without inconvenience or danger, to permit the operator to start the engine with a minimum exertion, the device being easily and conveniently operated and capable of being applied to or removed from 25 the engine practically as a unit without the necessity of altering the construction of said engine.

Another object is to provide a device which 30 will be out of engagement with the engine shaft and idle during the time the engine is running and which is only thrown into engagement with the engine shaft when it is desired to start the engine.

With these objects in view the invention 35 consists in the novel construction and arrangement of parts, hereinafter described, illustrated in the accompanying drawings, and particularly pointed out in the appended claims; it being understood that various 40 changes in the form, proportions, size and minor details of construction may be made within the scope of the appended claims without departing from the spirit or sacrificing any of the advantages of the invention. 45

Referring to the accompanying drawings: Figure 1 is a top plan view of a portion of an automobile chassis and engine showing my explosive engine starter applied thereto. 50 Fig. 2 is an enlarged longitudinal sectional view taken through my explosive engine starter. Fig. 3 is a top plan view of a portion of my device. Fig. 4 is a side elevation of a portion of my device. Fig. 5 is a detail perspective view of the operating lever. Fig. 6

is a detail perspective view of the mechanism which holds the clutch members normally out of engagement with each other. Fig. 7 is a transverse section through the device.

Similar numerals of reference indicate 60 corresponding parts throughout the several figures of the drawings.

Referring more especially to the construction illustrated in the accompanying drawings, the numeral 1 indicates a portion of the 65 chassis of an automobile, and the numeral 2 the engine which may be of any usual type of internal combustion engine.

The numeral 3 indicates the engine shaft to which shaft is secured by means of the pin 4 70 the usual cylindrical member 5 which is provided with the clutch member 6 such as is ordinarily provided upon the engine shaft for the purpose of cranking the engine. Secured to the cylindrical member 5 is a clutch 75 member 7 provided with a series of teeth 8. The usual clutch member 9 is connected to the inner extremity of the shaft 10 by means of a screw 11.

Loosely mounted upon the member 9 is a 80 sliding sleeve 12 which is provided with a spoke 13, which supports a segment 14 provided with a peripheral groove 15, said segment adapted to rotate around the outside of the housing 16 as best shown in Fig. 7 of 85 the drawings. To the inner extremity of the sleeve 12 is connected a clutch member 17 in any suitable and well known manner, said clutch member being adapted to engage the clutch member 7 as will be herein- 90 after described.

A coil spring 18 is located around the member 9 and interposed between the externally screw threaded member 19 and the sleeve 12, thus tending to normally throw 95 the clutch member 17 into engagement with the clutch member 7. The member 19 is provided with a socket 20, which receives the extremity of the member 9, said member 19 being suitably journaled in the bearing 100 21 mounted upon the chassis 1. The clutch member 9 is normally held out of engagement with the clutch member 6 by means of the usual spring 22. A chain 23 is attached to the hub 24 of the segment 14 by any 105 suitable means such as the screw 25, a coil spring 26 being attached to the extremity of said chain, said coil spring being carried upon a clip 27, which engages the chassis as shown in Fig. 7. The spring 26 thus nor- 110

mally tends to hold the segment 14 in the position shown in Fig. 7.

A pair of arms 28 and 29, provided with inclined forward faces 30 are bolted to the base of the engine 2, the forward inclined faces being adapted to be engaged by the spoke 13 of the segment as will be herein-after described. Connected at one end of the segment 14 by means of the screw 31 is a chain 32, which is located around the groove in the segment and which passes over the compound pulley 33. The compound pulley is composed of a large sheave 34 and a small sheave 35, which are preferably made integral, the chain 32 passing first around the large sheave and then up and around the smaller sheave. The chain is then continued back along the chassis and around the segment 36, said segment being mounted for rotation upon the usual brake rod 37, the hand lever 38 being fixedly connected to said segment and off-set therefrom at 39. It will be understood that the segment is merely mounted upon the usual brake rod as a matter of convenience, but it may be pivoted in any suitable position upon the machine.

A bracket 40 is mounted in a suitable position upon the dash board of the machine, said bracket being provided with a pair of spaced arms 41, which receive the operating lever, friction blocks 42 of rubber or similar material being provided upon the side faces of the lever. Thus when the lever is in the inoperative position as shown in Fig. 5, the arms 41 frictionally engaging the blocks 42, will hold the lever against displacement.

Mounted upon the forward end of the engine is a horizontally disposed bracket 43 upon which bracket is pivotally mounted the plate 44, the spring 45 passing around the pivot 46 and having its extremities bearing against the edges of the bracket and the plate 44, thus normally holding the plate in contact with the stop screw 47 as best illustrated in Figs. 3 and 6. A roller 48 is mounted at the forward extremity of the plate 44 and arranged to engage the segment 14 as shown in Fig. 3. This mechanism is for the purpose of preventing the teeth upon the clutch member 17 from riding over the teeth upon the clutch member 7 upon the return of the segment to the normal position.

The operation of the device is as follows: The parts being normally held in the position shown in the several figures of the drawings, the arm 13 of the segment 14 is held in engagement with the inclined face of the arm 29, thus holding the clutch member 17 out of engagement with the clutch member 7. When it is desired to start the engine the hand grip 49 of the operating lever is grasped and pulled forwardly, the segment 14 being revolved, bringing the

spoke 13 out of engagement with the inclined face of the arm 29 and allowing the clutch member 17 to engage the clutch member 8, thus rotating the engine shaft 3. The segment 14, contacting with the roller 48, as it moves in this direction will cause the plate 44 to move upon the pivotal point 46 allowing the spring 45 to slide the sleeve 12 rearwardly, throwing the clutch member 17 into engagement with the clutch member 7. As the segment 14 completes its movement the spoke 13 will engage the inclined face of the arm 28, thus throwing the clutch members again out of engagement as the engine is started. The spring 45 will then throw the plate 44 into the normal position, the roller 48 engaging the segment 14 and holding the clutch members 17 and 7 apart as shown in Fig. 3 and as the operating lever is released the coil spring 26 will pull the segment and its accompanying parts into the normal position. As the clutch members are held apart by means of the plate 44 and roller 48 the teeth of the clutch member 17 will not click or ride over the teeth of the clutch member 17 upon the return movement. It will thus be seen that at all times while the device is not in operation, either while the engine is running or dead the clutch member 17 will be held out of engagement from the clutch member 7 and said clutch members are only thrown into engagement during the operation of starting the engine.

The numeral 50 indicates an adjusting screw which is provided for the purpose of taking up slack in the chain 32, said adjusting screw being located through the lug 51 in the segment 36 and bearing against the shoulder 39 of the operating lever.

Although the drawings and above specification disclose the best mode in which I have contemplated embodying my invention I desire to be not limited to the details of such disclosure, for, in the further practical application of my invention, many changes in form and construction may be made, as circumstances require or experience suggests, without departing from the spirit of the invention, within the scope of the appended claims.

I claim:

1. In an explosive engine starter, comprising in combination with an explosive engine shaft, a receiving clutch member fixedly mounted upon the shaft of said engine, a second shaft arranged in alinement with the engine shaft, a movable clutch member slidably mounted upon said second named shaft, a radial spoke provided upon said movable clutch member, a segment carried by said spoke, arms supported upon the engine base and located adjacent each side of said movable clutch member, inclined faces provided upon said arms, said spoke adapted to en-

gage said inclined faces, means for normally holding said spoke in engagement with one of said inclined faces, means for rotating said segment, a plate pivotally mounted upon said engine, a roller mounted upon the outer extremity of said plate and means for holding said roller in engagement with said segment.

2. In an explosive engine starter, comprising in combination with an explosive engine shaft, a receiving clutch member fixedly mounted upon the shaft of the engine, a second shaft arranged in alinement with said engine shaft, a movable clutch member slidably mounted upon said second named shaft, a radial spoke provided upon said clutch member, a segment carried by said clutch member, arms supported upon the engine base and located adjacent each side of said movable clutch member, inclined faces provided upon said arms, said spoke adapted to engage said inclined faces, means for normally holding said spoke in engagement with one of said inclined faces, a plate pivotally mounted upon said engine, means for limiting the movement of said plate in one direction, a roller mounted upon the outer extremity of said plate, means for normally holding said plate in engagement with said limiting means, said roller arranged to contact with said segment, a flexible member

©

30 with said limiting means, said roller arranged to contact with said segment and means for rotating said segment.

3. In an explosive engine starter, comprising in combination with an explosive engine shaft, a receiving clutch member fixedly mounted upon the shaft of the engine, a second shaft, arranged in alinement with said engine shaft, a movable clutch member slidably mounted upon said second named shaft, a radial spoke provided upon said clutch member, a segment carried by said clutch member, arms supported upon the engine base and located adjacent each side of said movable clutch member, inclined faces provided upon said arms, said spoke adapted to engage said inclined faces, means for normally holding said spoke in engagement with one of said inclined faces, a plate pivotally mounted upon said engine, means for limiting the movement of said plate in one direction, a roller mounted upon the outer extremity of said plate, means for normally holding said plate in engagement with said limiting means, said roller arranged to contact with said segment, a flexible member

connected to said segment and an operating lever connected to said flexible member.

4. In an explosive engine starter, comprising in combination with an explosive engine shaft, a receiving clutch member fixedly mounted upon the shaft of the engine, a second shaft, arranged in alinement with said engine shaft, a movable clutch member slidably mounted upon said second named shaft, a radial spoke provided upon said clutch member, a segment carried by said clutch member, arms supported upon the engine base and located adjacent each side of said movable clutch member, inclined faces provided upon said arms, said spoke adapted to engage said inclined faces, means for normally holding said spoke in engagement with one of said inclined faces, a plate pivotally mounted upon said engine, means for limiting the movement of said plate in one direction, a roller mounted upon the outer extremity of said plate, means for normally holding said plate in engagement with said limiting means, said roller arranged to contact with said segment, a compound pulley, a chain connected to said segment and passing around said compound pulley and an operating lever connected to said chain.

5. In an explosive engine starter, comprising in combination with an explosive engine shaft, a receiving clutch member fixedly mounted upon the shaft of said engine, a second shaft in alinement with said engine shaft, a movable clutch member slidably mounted upon said second shaft, a radial spoke provided upon said movable clutch member, a segment carried by said spoke, a half-round casing located beneath said clutch members, cam members supported upon said casing and provided with inclined faces, a spring attached to said segment and to a suitable support and adapted to hold said spoke in engagement with one of said inclined faces, means for rotating said segment, a bracket mounted upon said engine, a plate fixedly mounted on said bracket, a roller mounted upon the outer extremity of said plate, means upon said bracket for limiting the movement of said plate in one direction and a spring upon said bracket arranged to hold said roller in contact with said segment.

In testimony that I claim the above, I have hereunto subscribed my name.

JAMES E. BINNS.
